Primary Examiner—Kay H. Chin*Attorney, Agent, or Firm*—Arthur G. Yeager[57] **CLAIM**

The ornamental design of a rack for infrared receiver pods of airplanes, as shown and described.

DESCRIPTION

FIG. 1 is an isometric top frontal view of a first embodiment of a rack for infrared receiver pods of airplanes showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is an isometric top frontal view of a second embodiment of a rack for infrared receiver pods of airplanes showing my new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof; and,

FIG. 14 is a left side elevational view thereof.
